(57) **CLAIM**

The ornamental design for a French press, as shown and described.

DESCRIPTION

FIG. 1 is a front elevation view of the design for the French press;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a perspective view thereof; and,

FIG. 8 is an exploded perspective view thereof.

The broken lines in the drawing views represent unclaimed portions of a French press, which are included for the purpose of illustrating unclaimed environment only, and forms no part of the claimed design.

The dash-dot broken lines in the drawing views define the bounds of the claimed design and form no part thereof.
